UNITED STATES PATENT OFFICE.

HENRY RICHARD HANCOCK, OF BURNSIDE, SOUTH AUSTRALIA, AUSTRALIA, ASSIGNOR
TO ALLIS-CHALMERS COMPANY, OF MILWAUKEE, WISCONSIN, A CORPORATION OF
NEW JERSEY.

JIGGING-MACHINE FOR DRESSING ORES.

965,294.

Specification of Letters Patent. Patented July 26, 1910.

Application filed August 31, 1904. Serial No. 222,896.

To all whom it may concern:

Be it known that I, HENRY RICHARD HANCOCK, mining engineer, a subject of the King of Great Britain, residing at Burnside, in the State of South Australia, in the Commonwealth of Australia, have invented certain new and useful Improvements in Jigging-Machines for Dressing Ores, of which the following is a specification.

10 This invention relates to jigging machines, and the object of the invention is to provide an apparatus of this character which is effective in operation and which secures certain novel results, all as hereinafter 15 more particularly pointed out.

In the drawings accompanying and forming a part of this specification I illustrate an organization involving my invention, which I will set forth in detail in the following 20 description, but I do not limit myself to the showing thus made, for material variations may be adopted within the scope of my claims succeeding said description.

The foregoing advantages, as well as 25 others possessed by the machine represented in the drawings, will be fully disclosed in the said description and in said drawings. Figure 1 is a side view partly in section of the hutch and jigging apparatus showing 30 my improvements. Fig. 2 is a sectional end view of the hutch and sieve showing tailings discharge, rubbers, and water pressure apparatus. Fig. 3 is a part plan of the hutch and sieve showing the rubbers between 35 the sides thereof. Figs. 4 and 5 are detail side view and plan respectively of my improved tailings discharge. Fig. 6 is a detail view of the steel shoe as attached to the cam lever. Figs. 7, 8, and 9 are detail sectional 40 views of the sleeves or protectors on the lever shaft.

A is the hutch mounted on suitable supports and divided into any suitable number of compartments A' by means of movable 45 divisions A² provided with india-rubber or other flaps A³.

Within the hutch A the sieve B is suspended to which is imparted an alternate rise and fall simultaneously with a forward 50 and backward motion by means of the cam C. The ore is fed on to the sieve at B' and the tailings carried over the discharge end B² into the tailings compartment D.

The tailings compartment D is provided 55 with an improved apparatus for automatic-

ally discharging the tailings at the end of the hutch A without undue loss of water. The apparatus consists of two or more valves E of iron or brass preferably conical in shape which fit into seatings E' in the 60 bottom of the hutch A. The seatings may be of iron or where the water is deleterious of wood and be readily renewed when worn from use. Each valve E is connected to a vertical rod E² provided with a lever F at its 65 upper end. The levers F are keyed to shafts F' extending across the top of the hutch A and may be arranged in pairs as shown in Figs. 4 and 5 by being connected or coupled at their upper ends by means of plates F². 70

A driving shaft G is provided across the hutch A on which are mounted two cams G' set at different angles. The shaft G is preferably revolved at about fourteen revolutions a minute and the cams G' as they revolve 75 engage reels F³ attached to the plates F² thereby lifting the vertical rods E² and opening the valves E alternately by means of the levers F. On the cams G' disengaging the reels F³ the vertical rods E² are released 80 and the valves E by their own weight fall into their seatings E'. Care must be taken that the rods E² and valves E combined are of sufficient weight to insure their effectively closing the seatings when released 85 from the cams G'. An automatic discharge of the tailings is thereby effected without undue loss of water from the hutch A and from the cams G' being mounted at different angles on the shaft G the valves E are 90 opened and closed alternately. If a large quantity of tailings is to be produced two pairs of valves E may be in operation at one time (as shown in Figs. 4 and 5 of the drawings). With a smaller quantity of tailings 95 a lesser number of valves may be employed while when treating very rich ore producing a still smaller quantity of tailings the apparatus can be thrown out of gear by turning the belt on to a loose pulley. 100

The hutch A at the discharge end B² of the sieve B is divided by means of a slanting partition H so fixed in the end of the hutch A that its upper end is about two inches from the end B² of the sieve B. Any slimes 105 which may escape on to the sieve B from the slime washers are carried by the flow of water over the end of the sieve B and the partition H and settling obliquely are caught by the partition H and run out 110

through the outlet H' at the bottom in the end of the hutch A. The tailings discharging from the end B² of the sieve B drop vertically underneath the slanting partition H 5 into the tailings compartment D from whence they are withdrawn through the valve openings E'.

In order to more effectively maintain the sieve B in position and prevent the water 10 from rising except through the sieve B I interpose rubbers of hardwood or other suitable material and india-rubber between the sides of the hutch A and of the sieve B in segments for the whole length thereof. The 15 hard wood is attached by means of a plate J' and bolts J² to the hutch and in use projects against the india-rubber R suitably attached to the sides of the sieve B.

For the purpose of treating heavy ores 20 and insuring the heavy particles of ore stuff being carried over the sieve I introduce water under regulated pressure to the sieve B with every pulsation thereof through the openings K provided with india-rubber flap 25 valves K². The water is supplied from an overhead cistern fitted say twelve feet or more above the level of the sieve according to the nature and density of the material under treatment kept full of water and connected by means of a pipe or launder K' 30 with the flap valves. Taps J are provided in the pipes K to regulate the supply. In practice the introduction of this water under regulated pressure has been found of the 35 greatest importance in improving the efficiency of the jig and preventing the tendency of the water to form a vacuum at the rising of the sieve as it also prevents the light waste on the top of the sieve from being drawn into the concentrates by suction 40 at the rising of the sieve. The flow of water upward through the sieve under regulated pressure further serves to keep the waste stuff in a state of buoyancy and to cause it 45 to be carried over with the tailings at the discharge end of the sieve.

In order to preserve and protect the longitudinal lever L which is actuated by the cam C from which motion is imparted to 50 the entire machine the end of the longitudinal lever so attached by the cam is provided with a cast steel shoe L' which may be fitted to it by a bolt L² and when worn out be readily renewable.

To economize the wear and tear on the longitudinal lever shafts M at each end of the hutch sleeves or protectors M' of iron or steel are attached to the shaft M. These 55 sleeves or protectors M' are fitted into brasses M² and are held in position by collars N at each end of the plumber block N'. The collars N are fastened by means of set screws N². The sleeves or protectors M' take the wear and tear off the cam lever shaft M and preserve the said shaft M

from the waste water and other deleterious water flowing from the valves O of the hutch A and may be readily renewed.

Upon the shafts M are fixed crank arms 5, to the inner ends of which are jointed 70 rods, each designated by 6, the rods rising from the respective crank arms, and being connected at their upper ends to the cross-rods 7 located above and near the opposite ends of the sieve. The sieve is flexibly suspended from these cross-rods 7. Connected to one of the cross-rods in any desirable way are radius links, as 8, said links being jointed to some relatively stationary part of the apparatus. 75

The foregoing is a brief description of a way of securing a vibratory motion of the sieve in the manner hereinbefore set forth.

It will be understood that the levers L are linked together, to secure their motion in 80 unison. A power shaft, as 9, is represented as situated below the inner ends of the two levers L and as provided with a substantially triangular cam, as 10. The shaft 9 may be operated in any desirable way. 90 Upon its rotation the cam 10 will engage the shoe L' to impart, through the intervening mechanism just set forth, an up and down and endwise reciprocatory motion to the sieve. 95

What I claim as my invention, and desire to secure by Letters Patent, is:—

1. In an apparatus of the class described, a hutch, a sieve mounted in the hutch for endwise and vertical reciprocatory motion, 100 the hutch having outlets at the delivery end of the sieve, a valve for each outlet, and automatic means for opening the valves at intervals and in alternation.

2. In an apparatus of the class described, 105 a hutch, a sieve arranged in the hutch for endwise and vertical reciprocatory movements, the hutch having outlets at the delivery end of the sieve, valves for controlling the outlets and provided with upwardly extending rods, levers connected with the rods above the valves, plates connecting the respective levers, and a shaft having cam devices disposed at different angles thereto and adapted to successively engage the plates. 110

3. In an apparatus of the class described, 115 a hutch, a sieve mounted in the hutch for endwise and vertical reciprocatory movements, and a partition at the delivery end of the sieve, serving to separate the slimes 120 from the tailings discharged from the sieve, said partition dividing the hutch into slimes and tailings receiving compartments.

4. In an apparatus of the class described, 125 a hutch, a sieve mounted in the hutch for endwise and vertical reciprocatory movements, a partition at the delivery end of the sieve, separating the hutch into slimes and tailings receiving compartments, said partition slanting toward the delivery end of 130

the sieve and serving to separate tailings from slimes delivered against its upper edge by the sieve and to direct the same into their appropriate compartments, the tailings

5 receiving compartment having outlets, a valve for each outlet, and automatic means for opening the valves at intervals and in alternation.

In testimony whereof I have hereunto set my hand in presence of two subscribing witnesses. 10
